UNITED STATES PATENT OFFICE.

WILLIAM H. BETTS, OF ST. LOUIS, MISSOURI, ASSIGNOR TO BETTS SOLE PROTECTOR COMPANY, OF ST. LOUIS, MISSOURI, A CORPORATION OF MISSOURI.

SOLE PROTECTOR.

Application filed May 8, 1920. Serial No. 379,754.

To all whom it may concern:

Be it known that I, WILLIAM H. BETTS, a citizen of the United States, and resident of St. Louis and State of Missouri, have 5 invented certain new and useful Improvements in Sole Protectors, of which the following is a specification containing a full, clear, and exact description, references being had to accompanying drawings, forming 10 a part thereof.

My invention relates to improvements in sole protectors, and has for its primary object the construction of a protector which may be driven into the sole or other part 15 of the shoe and which will automatically clinch within the material and thereby not pass through the sole and require any subsequent clinching, this invention being an improvement on the sole protector previously 20 patented by me on July 15, 1919, Patent No. 1,310,050.

In the drawings:

Fig. 1 is a side elevation of my protector;

Fig. 2 is a sectional elevation showing the 25 same applied to the sole of a shoe, a portion thereof being broken away;

Fig. 3 is a bottom plan view;

Fig. 4 is a top plan view; and

Fig. 5 is a side elevation of a modified 30 form.

Referring to the drawings:

6 is the combined driving head and wearing plate, substantially elliptical and provided with prongs 7 formed at right angles 35 to the head 6. The inside and outside face of each prong is parallel, thus making the prongs of uniform thickness throughout. The prongs 7 are also of uniform width 40 throughout. The lower edge of each prong is curved, as at 8. The curvature is preferably accurately determined by the thickness of the prong, the curvature being the arc of a circle whose radius is equal to the thickness of the prong. This I deem is the 45 preferable way of forming the curvature of the lower edge or driving edge of the prongs.

The prongs are formed or stamped integral with the head 6 and being of uniform 50 thickness and width and having the lower rounded edge as described, the same when driven home would curve into the material

as illustrated in Fig. 2 and clinch themselves into the material without entirely penetrating the same.

In Fig. 5 I have shown a slightly modified form of prong, the modification residing solely in the surface of their lower ends or faces. In the modified form illustrated in Fig. 5 the prongs are formed with plane 60 angular faces 9, which are formed at an angle of about forty-five degrees or less than a right angle. The preferable angle in the modified form illustrated in Fig. 5 is substantially an angle of forty-five 65 degrees.

Having fully described my invention what I claim is:

1. A sole protector comprising a relatively thin and flat combined driving head 70 and wear plate and a pair of prongs formed integral with the ends of said plate, said prongs being parallel before being driven and of uniform thickness and widths and being of the same thickness as the driving 75 head, and each prong having its opposing faces parallel and each prong being provided on its lower outer edge with a curved face which in conjunction with the straight inner face forms a driving point, and to 80 cause the prongs to curve inwardly toward each other, the curvature of the edge substantially corresponding with the arc of a circle whose radius is equal to the thickness of the prong.

2. A protector for soles and the like comprising a relatively thin and flat combined driving head and wear plate and a pair of prongs formed integral with said driving head and wear plate, said prongs projecting from said head and being parallel to each other, each prong having parallel opposing faces and provided on the outer faces of their lower ends with upwardly and outwardly inclined surfaces which act 95 in conjunction with the inner surfaces of the prongs to form driving points, and which also act to cause the said prongs to uniformly curve inwardly toward each other.

In testimony whereof, I have signed my name to this specification.

WILLIAM H. BETTS.
